M. CIACCIA.

BACK DRAFT PREVENTING CHIMNEY COWL.

APPLICATION FILED OCT. 29, 1919.

Patented June 15, 1920.

FIG. 2.

Inventor
M. Ciaccia

J. H. Bryant.
Attorney

UNITED STATES PATENT OFFICE.

MICHAEL CIACCIA, OF ALBANY, NEW YORK.

BACK-DRAFT-PREVENTING CHIMNEY-COWL.

1,343,763.

Specification of Letters Patent. Patented June 15, 1920.

Application filed October 29, 1919. Serial No. 334,283.

To all whom it may concern:

Be it known that I, MICHAEL CIACCIA, a citizen of the United States of America, residing at Albany, in the county of Albany 5 and State of New York, have invented certain new and useful Improvements in Back-Draft-Preventing Chimney-Cowls, of which the following is a specification.

The primary object of the invention is 10 the provision of a chimney cowl or top adapted to provide ready outlet for the products of combustion from the chimney while preventing any back-draft caused by air currents from without, the structure possessing great simplicity and being easy and 15 inexpensive to manufacture.

A further object of the invention is to provide a chimney top formed of metal or tile having adjustable means whereby main outlets are provided either for a direct draft in 20 the top of the device or at the sides thereof farthest from the direction of travel of prevailing winds for the locality in which the chimney is positioned.

25 A still further object of the invention is to provide an economical chimney top preventing any down-drafts of the smoke or gases without interfering with the normal up-draft of the chimney, provision being 30 made to accelerate the draft of the chimney during the passing of the products of combustion through the device.

With these general objects in view, the invention consists of the novel combination 35 and arrangement of parts hereinafter fully described, illustrated in the accompanying drawing and then claimed.

In the drawing forming a part of this application and in which like reference 40 numerals designate corresponding parts throughout the several views,

Figure 1 is an elevational view of one side of the invention partially broken away with the top closed,

45 Fig. 2 is a top plan view thereof,

Fig. 3 is an elevational view of an adjacent side of the invention from that shown in Fig. 1 and with the top lids open and

Fig. 4 is a transverse sectional view taken 50 upon line IV—IV of Fig. 3.

It being understood that my invention may be formed of any suitable material such as sheet metal or fire clay and may be either oblong or square in shape, one form of the 55 invention is herein illustrated by way of example formed of sheet metal and mounted

upon the top of a chimney 11 for receiving the products of combustion from the flue 12 thereof. The invention includes a casing 13 rectangular in cross section having the upper 60 portion 14 thereof flaring downwardly meeting a lower portion 15 which tapers downwardly, the point of meeting of the sections 14 and 15 forming a waist 16 while a lower tubular extension 17 of the section 15 65 is mounted in the chimney flue 12.

The lower section 15 is provided with opposite openings 18 in two of its sides while the section 14 has slightly larger openings 19 in its corresponding sides above the plane 70 of the openings 18. Hinged lids 20 of any suitable form are provided for the open top of the cowl, one manner of carrying out the invention being the provision of two lids 20 hinged to the opposite edges 21 of the 75 side walls of the cowl above the openings 19. The lids 20 may be closed when it is desired to cut off the direct outlet for the vertical path of travel of the products of combustion from the flue 12 although the lids 20 80 may be opened as illustrated in Fig. 3 of the drawing for flatly engaging the opposite sides of the cowl above the plane of the openings 19 and thereby forming a direct vertical passage through the device. It will 85 be understood that in the place of hinged lids 20, my invention also contemplates the placing of a removable plate or tile over the open top of the cowl whenever desired.

Oblique partitions or baffle plates 22 are 90 provided in the cowl having their lower ends mounted at the waist line 16 thereof and extending upwardly between opposite sides 23 of the cowl which are provided with outlet openings 24 above the plane of the upper 95 openings 19 in the adjacent sides thereof. The partitions 22 are convergently arranged and terminate substantially at the lower edges of the opposite openings 24 as illustrated by dotted lines in Fig. 1 of the drawing. Relatively shorter baffle plates or partitions 25 are similarly provided within the cowl between the sides 23 thereof being connected to the cowl substantially at the line of jointure 26 of the section 15 and neck 17. 100 105

It will be seen that the upper partitions 22 extend above the plane of the side openings 19 forming a contracted neck or throat 27 between the upper ends of the partitions 22 while the partitions 25 terminate above the 110 plane of the openings 18 providing a contracted throat 27' between the upper ends of

the partitions 25 substantially equal in size to the throat 27 and axially arranged with respect thereto. Suitable lids or shields 28 are provided for the outlet side openings 24 and 5 are herein illustrated in the form of hoods carried by the sides 23 of the cowl. While these shields 28 are herein illustrated of a certain form, it will nevertheless be understood that they may be hinged constituting 10 side lids if desired and may be entirely removable and adjustable to different positions if the circumstances of the particular installation renders such a construction desirable.

15 The general operation of the invention will be fully understood from this detailed description thereof. When the lids 20 are thrown back to their open positions as illustrated by dotted lines in Fig. 1, a direct vertical up-draft is provided through the cowl from the flue 12, the products of combustion passing through the contracted throats 27' and 27 outwardly of the top of the chimney. Air may freely enter through the 20 openings 18 and 19 into the back-draft preventing pockets 29 and 30 formed respectively outwardly of the partitions 25 and 22, thereby increasing the velocity of the up-draft through the cowl by preventing any 25 pocketing or holding effect upon the outgoing products of combustion by the cowl structure. When the top draft is not desirable in the particular location of the chimney 11, the lids 20 are closed and the 30 products of combustion pass through the contracted throats 27' and 27 outwardly through the side openings 24. When the shields 28 are obliquely mounted over the openings 24, the wind is prevented from blowing into the 35 openings 24 but as the shields 28 may be removed at will, the sides 23 in which the openings 24 are positioned are arranged out of the direct line of travel of the prevailing winds of that locality. In the event of the 40 products of combustion, smoke and gases from the flue 12 being blown backwardly in the cowl, the same may readily escape from the back-draft pockets through the openings 18 and 19 and in the event that it becomes 45 desirable to do so, both the top of the cowl as well as the openings 24 might be closed for greatly reducing or choking the up-draft of the flue 12 but still maintaining an open passage through the cowl outletting at the openings 18 and 19.

50 While the form of my invention herein set forth and described is believed to be the preferable embodiment thereof, it is nevertheless to be understood that minor changes 55 may be made therein in proportion, form and details of construction without departing from the spirit and scope of the invention as claimed.

My invention is also serviceable for 60 ventilating purposes, the hoods 28 being readily

removable by releasing the hinge hooks 28' thereof. An adjustable plate 20' is at all times maintained centrally upon the top of the casing 13 directly above the throat 27, preventing snow and rain from entering the 70 throat when the lids 20 are open.

What I claim as new is:—

1. A device of the class described comprising a casing having a flaring waist portion, with openings in two of its opposite 75 sides above and below said waist portion, means for mounting the casing in the top of a chimney, inclined partitions within the casing inwardly of said side openings forming contracted necks at the inner free 80 ends of the partitions within the path of travel of products of combustion from the chimney.

2. A device of the class described comprising a casing having a flaring waist portion, with openings in two of its opposite 85 sides above and below said waist portion, means for mounting the casing in the top of a chimney, inclined partitions within the casing inwardly of said side openings forming 90 contracted necks at the inner free ends of the partitions within the path of travel of products of combustion from the chimney, the sides of the casing unprovided with said openings having outlet openings adjacent the uppermost throat and adjustable closing means for the top of the casing.

3. A chimney cowl comprising a casing having an enlarged waist line dividing the cowl into upper and lower sections, with said 100 sections having openings therein positioned above each other in opposite walls of the casing, inwardly and upwardly inclined partitions within the casing with their lower ends mounted adjacent the waist line thereof of forming opposite pockets inwardly of the upper ones of said openings, similar inwardly projecting partitions within the casing mounted adjacent the lower end of the lower section forming pockets inwardly 105 of the lower openings, the said pairs of partitions forming contracted throats within the casing in the path of travel of products of combustion therethrough.

4. A chimney cowl comprising a casing 115 having an enlarged waist line dividing the cowl into upper and lower sections, with said sections having openings therein positioned above each other in opposite walls of the casing, inwardly and upwardly inclined 120 partitions within the casing with their lower ends mounted adjacent the waist line thereof of forming opposite pockets inwardly of the upper ones of said openings, similar inwardly projecting partitions within the casing mounted adjacent the lower end of the lower section forming pockets inwardly 125 of the lower openings, the said pairs of partitions forming contracted throats within the casing in the path of travel of products of 130

combustion therethrough, a neck carried by the lower end of the lower section adapted for seating within a chimney flue, the opposite sides of the upper section of the cowl 5 which are unprovided with said openings having outlet openings adjacent the upper ends of the partitions of the upper section and adjustable closure means for the open top of the cowl.

10 5. A chimney cowl comprising a casing having an enlarged waist line dividing the cowl into upper and lower sections, with said sections having openings therein positioned above each other in opposite walls of 15 the casing, inwardly and upwardly inclined partitions within the casing with their lower ends mounted adjacent the waist line thereof forming opposite pockets inwardly of the upper ones of said openings, similar inwardly projecting partitions within the casing 20 mounted adjacent the lower end of the

lower section forming pockets inwardly of the lower openings, the said pairs of partitions forming contracted throats within the casing in the path of travel of products of combustion therethrough, a neck carried by the lower end of the lower section adapted for seating within a chimney flue, the opposite sides of the upper section of the cowl which are unprovided with said 25 openings having outlet openings adjacent the upper ends of the partitions of the upper section, adjustable closure means for the open top of the cowl, removable hoods for the said outlet openings carried by the opposite sides of the upper section whereby the outlet openings or the open top of the upper section are adapted for exhausting the products of combustion therethrough at will. 30

In testimony whereof I affix my signature. 35

MICHAEL CIACCIA.
